UNITED STATES PATENT OFFICE.

HENRY McDERMOTT, OF NORWICH, CONNECTICUT.

COILER FOR CARDING-MACHINES, &c.

SPECIFICATION forming part of Letters Patent No. 518,675, dated April 24, 1894.

Application filed June 23, 1893. Serial No. 478,672. (No model.)

To all whom it may concern:

Be it known that I, HENRY McDERMOTT, a citizen of the United States, residing at Norwich, in the county of New London and State 5 of Connecticut, have invented a certain new and useful Improvement in Coilers for Carding-Machines, &c., which improvement is fully set forth and described in the following specification, reference being had to the accompanying sheet of drawings.

This invention relates to mechanism for coiling into suitable cans so called sliver as the latter is delivered from carding machinery or from drawing frames, as commonly used 15 in the manufacture of cotton into roping or yarn.

The object of my invention is to provide an alarm which, used in connection with the coiler proper, will promptly notify the attendant whenever the can becomes filled with the coiled sliver and this I accomplish by the addition of very simple mechanism, as illustrated in the drawings, in which—

Figure 1 is a side elevation of a can and 25 coiler complete, having attached thereto my newly invented alarm mechanism. Fig. 2 is an elevation of the coiler head with its case in central, vertical section and Fig. 3 is a plan view with the hinged cap g' removed. 30 Fig. 4 is an enlarged, plan, view similar to Fig. 3 but with the condensing rolls and their driving mechanism removed. Fig. 5 is a side elevation of a portion of the disk that carries the coiler-tube, showing in proper relation thereto the alarm mechanism which forms the 35 essential feature of my invention. Figs. 6, 7 and 8 show, detached, certain of the elements of said alarm mechanism, all being hereinafter described in detail.

40 The coiler mechanism, as well as the mechanism for supporting and revolving the can, are here shown substantially the same as now in common use and I therefore make no claim to these mechanisms.

45 The reference letter a indicates the driving shaft of the coiler and can-rotating mechanisms, which shaft may receive motion from any convenient part of a carding machine, or railway head, as the case may be. This shaft 50 a bears a miter gear a' which meshes with a corresponding gear b' secured to a vertical

shaft b which latter has secured to its upper end a miter gear b^2 and to its lower end a spur gear b^3 . Gear b^3 meshes with and drives a somewhat larger gear c located on a stud c' 55 and upon the same stud, adapted to rotate with gear c , is a small gear c^2 that meshes with a larger gear c^3 loosely mounted upon the lower end of shaft b . Secured to the side of gear c^3 is a smaller gear c^4 that meshes with a gear c^5 which in turn meshes with and drives 60 a large gear d whose upper portion is formed as a table d' upon which a can e may be placed. The arrangement of the described train of gearing is such that the can support- 65 ing table d' revolves very slowly.

f denotes a casing which projects forward over the table d' and to the rear side of this casing is hinged a similar casing g to which is hinged a cap or cover g' . The casing f is 70 formed with a large circular opening whose annular walls extend inward to provide a ledge f' upon which is loosely seated a disk h with circumferential gear teeth that mesh with a gear f^2 secured to the shaft b . When 75 shaft b is caused to revolve the disk h is also set in revolution.

To the upper side of disk h is secured a tube h' , set diagonally at such an inclination that its lower, or delivery, end is over a point mid-way the center and circumference of the can while its upper end is over the center of the can and immediately under a pair of condensing rolls $i-i'$ journaled in bearings secured in the hinged casing g . The shafts of these condensing rolls bear meshing gears $k-k'$ and one of said shafts has also a miter gear k^2 that is driven by the gear b^3 already referred to. When the described mechanisms are in operation the can e is revolved slowly in one direction while the coiler-disk h is revolved somewhat faster in the opposite direction and as the sliver passes downward between the rolls $i-i'$ it enters the tube h' and is guided outward and delivered into can e . The combined movements of the can and disk h cause the sliver to continually coil upon itself within the can until the latter is filled. 85 90 95

The mechanisms thus far referred to are old and well known and I have described 100 them in detail only for the purpose of explaining clearly my improvement.

Secured to the inner side of the casing g is a bracket-arm m whose free end is extended to a point over an annular flange or rib h^2 on the upper side of disk h , and upon this extended-end of bracket m is journaled a roller n formed with a head n' of disk form which latter is cut with ratchet teeth as shown. Pivoted to the bracket m is a lever o one of whose ends extends substantially parallel 5 to with said bracket and terminates immediately over the ratchet disk n' . The other arm of lever o is bent laterally so that it may pass outward through an opening in the casing g and terminates with a ball which forms 10 a clapper for use with a bell p secured to the outside of said case g . The arrangement of the ratchet-disk, lever and bell is such that the rotation of said ratchet-disk will serve to ring the bell. It will be noticed that, normally, the roller n (that bears the ratchet-disk) is not in contact with the flange h^2 of the disk h . When the complete coiler is in 15 service the sliver accumulates in the can until the latter is filled. As the sliver continues to coil itself upon the filled can it engages the lower face of disk h and crowds said disk upward, as shown in dotted lines in Fig. 5,

thus forcing the flange h^2 into engagement with the roller n and causing the latter to rotate. This simultaneously sets in revolution 30 the ratchet-disk n' causing lever o to vibrate and ring the bell p and thus the attention of the attendant is called to the filled can. By regulating the weight of disk h the sliver may be coiled in the can with any desired degree 35 of compactness.

My alarm attachment may be cheaply applied to coilers now in common use and will serve to avoid much of the waste and annoyance that now result from allowing the cans 40 to become too tightly packed with sliver.

Having described my invention, I claim—

In a coiler, in combination, a loosely supported coiler-disk and mechanism for revolving the same, a ratchet-disk located in the 45 vertical path of said disk, and a bell and clapper; said clapper being located in the path of the ratchet-disk and actuated thereby, substantially as specified.

HENRY McDERMOTT.
